DISPENSING DEVICE

Lorraine L. Manly, Fort Sam Houston, Tex.

Application January 20, 1942, Serial No. 427,511

5 Claims. (Cl. 221—104)

This invention relates to a dispensing device, and it is primarily an object of the invention to provide a device of this kind with means whereby powdered or granulated substances in predetermined bulk may be poured from cans, jars or other containers.

It is also an object of the invention to provide a device of this kind which can be readily applied to a container and wherein the device is so constructed as to afford maintenance of the container, or more particularly the contents thereof, in a highly sanitary condition, or especially when the device is used in connection with tooth powder cans, or sugar containers commonly used in restaurants.

The invention consists in the details of construction and in the combination and arrangement of the several parts of my improved dispensing device whereby certain important advantages are attained, as will be hereinafter more fully set forth.

In order that my invention may be the better understood, I will now proceed to describe the same with reference to the accompanying drawing, wherein:

Figure 1 is a sectional view taken through a dispensing device constructed in accordance with an embodiment of my invention, and in applied position, the associated container being shown in fragment;

Figure 2 is also a sectional view taken through the device and the adjacent portion of an associated container, the assembly being inverted and showing certain of the parts in a second position; and

Figure 3 is a sectional view taken through the cap of the device unapplied.

As disclosed in the accompanying drawing, C denotes an end portion of a conventional container such as used for holding sugar, tooth powder, or other comminuted materials and in connection with the open end thereof my improved device is adapted to be employed.

My improved device as herein embodied comprises a base member or plate 1 of required configuration and dimensions and which has its marginal portion defined by a surrounding flange 2 whereby the device may be readily slipped upon the open end portion of the container C. The central portion of the base member or plate 1 is formed to provide an outstanding and relatively large hollow casing 3 herein disclosed as substantially semi-spherical in form with the larger or flat face 4 open. The central part of the casing 3 is provided with an opening 5 defined by an outstanding sleeve 6 of desired length.

Snugly and slidably disposed through the sleeve 6 is a tubular member 7 having its inner end 8 closed, and with said inner closed end provided with a surrounding outstanding bead 9 which

serves as a stop for contact with the portion of the casing 3 surrounding the opening 5 to limit the extent of outward movement of the member 7. The outer end portion of the tubular member 7 is 5 radially enlarged, as at 10, to provide an inwardly facing shoulder 11 for contact with the outer end of the sleeve 6 whereby is limited the extent of inward sliding movement of the tubular member 7. This tubular member 7 is of such length as to have 10 its inserted or closed end 8 closely adjacent to the open face 4 of the casing when the member 7 is at the limit of its inward movement, but with the portion of the member 7 within the casing 3 being entirely housed within the casing.

15 The inserted end portion of the member 7 is provided in its wall with the relatively large and diametrically opposed openings 12 each of which being rectangular in form, although I do not wish to be understood as limiting myself to any particular style of opening. Each of these openings 12 also preferably extends from the inserted closed end 8 of the sleeve to a point immediately adjacent to the opening 5 when the member 7 is at the limit of its inward movement, as is clearly illustrated in Figure 1 of the drawing.

Snugly and slidably mounted upon the sleeve 6 is a cap member 14, said cap 14 fitting upon the sleeve 6 sufficiently loose to permit free movement of the cap 14 along the sleeve 6 without binding. 20 The enlarged portion 10 of the member 7, however, is of a major diameter sufficiently greater than that of the sleeve 6 to bind against the inner or closed end portion of the cap 14 sufficiently tight to cause the cap 14 and the member 7 to 25 move in unison.

The lower or open end of the cap 14 is defined by an outstanding surrounding skirt 15 substantially semi-spherical in form and which, when the member 7 is at the limit of its inward movement, has close engagement over the casing 3. As is illustrated in Figure 1, the skirt 15 when the member 7 is at the limit of its inward movement substantially entirely covers the casing 3. The enlargement 10 of the member 7 is preferably produced by properly expanding the member 7 after the same has been initially inserted through the sleeve 6.

40 The container C with my improved device thereon is normally in an upright position. When it is desired to dispense the contents of the container C, said container C with the applied device is inverted, whereupon the material within the container C will flow through the openings 12 into the member 7. It is believed to be obvious that normally the member 7 is at the limit of its inward movement. As the material flows through the openings 12 it will properly fill the member 7 upon the closed head 16 of the cap member and which head at that time serves as a closure for the outer end of the member 7. Out-

ward pull is then imposed upon the cap 14 which will result at the same time in outward movement of the member 7, bringing the bead 9 into contact with the wall of the casing 3, thus limiting the outward movement of the member 7. The cap 14 is then pulled down off from the member 7, and during which operation the cap member 14 serves as a cap to receive the material within the member 7. It is at this time to be pointed out that the sleeve 6 is of sufficient length to close the openings 12 when the member 7 is in its outer or withdrawn position, as clearly illustrated in Figure 2.

After the material within the removed cap 14 has been discharged as desired the cap 14 is re-applied and the various parts of the device returned to their normal positions as illustrated in Figure 1.

It is believed to be apparent that the casing 3 serves in the fashion of a funnel to facilitate the flow of material from the container C through the openings 12 into the member 7, and it is also believed to be obvious that the construction of the dispensing device is such as to allow the desired flow of the material within the container C into the device to be gravitational.

From the foregoing description it is thought to be obvious that a dispensing device constructed in accordance with my invention is particularly well adapted for use by reason of the convenience and facility with which it may be assembled and operated.

I claim:

1. A dispensing device comprising a member adapted to be disposed over the discharge opening of a container, said member having an opening, an outstanding sleeve carried by the member and surrounding the opening, a tubular member freely slideable through the sleeve, the inner end of the tubular member being closed and the outer end open, an inlet opening in the side wall of the tubular member adjacent to the closed end thereof, and a cap freely slideable on the tubular member, the outer end portion of the tubular member having close frictional contact with the side wall of the cap to allow said cap and tubular member to have unitary outward movement, said tubular member being provided with means for limiting the extent of its movement in either direction, the opening of the tubular member when at the limit of its inward movement being below the adjacent portion of the sleeve.

2. A dispensing device comprising a member adapted to be disposed over the discharge opening of a container, said member having an opening, an outstanding sleeve carried by the member and surrounding the opening, a tubular member freely slideable through the sleeve, the inner end of the tubular member being closed and the outer end open, an inlet opening in the side wall of the tubular member adjacent to the closed end thereof, a cap freely slideable on the tubular member, the outer end portion of the tubular member having close frictional contact with the side wall of the cap to allow said cap and tubular member to have unitary outward movement, said tubular member being provided with means for limiting the extent of its movement in either direction, the opening of the tubular member when at the limit of its inward movement being below the adjacent portion of the sleeve, the means for limiting the movement of the tubular member comprising a surrounding bead at its closed end for contact with the member, and an

inwardly facing surrounding shoulder at its outer end portion for contact with the outer end of the sleeve.

3. A dispensing device comprising a member adapted to be disposed over the discharge opening of a container, said member having an opening, an outstanding sleeve carried by the member and surrounding the opening, a tubular member freely slideable through the sleeve, the inner end of the tubular member being closed and the outer end open, an inlet opening in the side wall of the tubular member adjacent to the closed end thereof, and a cap freely slideable on the tubular member, the outer end portion of the tubular member having close frictional contact with the side wall of the cap to allow said cap and tubular member to have unitary outward movement, said tubular member being provided with means for limiting the extent of its movement in either direction, the opening of the tubular member when at the limit of its inward movement being below the adjacent portion of the sleeve, the portion of the member having the opening being outwardly disposed to provide a parti-spherical casing.

4. A dispensing device comprising a member adapted to be disposed over the discharge opening of a container, said member having an opening, an outstanding sleeve carried by the member and surrounding the opening, a tubular member freely slideable through the sleeve, the inner end of the tubular member being closed and the outer end open, an inlet opening in the side wall of the tubular member adjacent to the closed end thereof, and a cap freely slideable on the tubular member, the outer end portion of the tubular member having close frictional contact with the side wall of the cap to allow said cap and tubular member to have unitary outward movement, said tubular member being provided with means for limiting the extent of its movement in either direction, the opening of the tubular member when at the limit of its inward movement being below the adjacent portion of the sleeve, the portion of the member having the opening being outwardly disposed to provide a parti-spherical casing, the inserted end portion of the tubular member when at the limit of its inward movement being housed within said casing.

5. A dispensing device comprising a member adapted to be disposed over the discharge opening of a container, said member having an opening, an outstanding sleeve carried by the member and surrounding the opening, a tubular member freely slideable through the sleeve, the inner end of the tubular member being closed and the outer end open, an inlet opening in the side wall of the tubular member adjacent to the closed end thereof, and a cap freely slideable on the tubular member, the outer end portion of the tubular member having close frictional contact with the side wall of the cap to allow said cap and tubular member to have unitary outward movement, said tubular member being provided with means for limiting the extent of its movement in either direction, the opening of the tubular member when at the limit of its inward movement being below the adjacent portion of the sleeve, the sleeve being of a length sufficient to close the opening in the side wall of the tubular member when said tubular member is at the limit of its outward movement.

LORRAINE L. MANLY.
